United States Patent Office

Des. 175,366
Patented Aug. 16, 1955

175,366

HINGE

Kurt Schoen, New Hyde Park, and Alfred O. Belaschk, Elmhurst, N. Y.

Application February 3, 1953, Serial No. 23,406

Term of patent 14 years

(Cl. D10—9)

FIG.2

FIG.4

FIG.1

FIG.3

Fig. 1 is a front elevational view of a hinge showing our new design, the hinge being shown in open position;

Fig. 2 is an end elevational view of the hinge shown in Fig. 1;

Fig. 3 is a front elevational view of the hinge with the hinge being shown in closed position; and

Fig. 4 is an end elevational view of the hinge in the position shown in Fig. 3.

We claim:

The ornamental design for a hinge, as shown.
